UNITED STATES PATENT OFFICE.

FREDERICK S. GLINES, OF SWAMPSCOTT, MASSACHUSETTS, ASSIGNOR TO LORENZ MUTHER, OF NEWTON, MASSACHUSETTS.

EYELET-SETTING DEVICE.

1,110,258.

Specification of Letters Patent. Patented Sept. 8, 1914.

Application filed April 27, 1914. Serial No. 834,599.

To all whom it may concern:

Be it known that I, FREDERICK S. GLINES, a citizen of the United States, residing in Swampscott, county of Essex, State of 5 Massachusetts, have invented certain new and useful Improvements in Eyelet-Setting Devices, of which the following is a specification, reference being had to the drawings accompanying the same and forming a part 10 thereof.

My invention relates to a device for setting eyelets or rivets in one or more of a plurality of layers of flexible material.

The object of my invention is to provide 15 an adjustable shoulder to limit the movement of the material above or beyond the setting shoulder.

In the drawings illustrating my device Figure 1 is a side elevation of my improved 20 eyelet setting device with the adjustable means secured thereto; Fig. 2 is a vertical sectional elevation of same; and Fig. 3 is a plan of same taken from the setting end of the device, or lower end as it appears in 25 Fig. 1.

In the drawings illustrating my invention, 1 is the body of the eyelet setting device and 2 is a threaded portion of the proper size and pitch of thread to enable it 30 to be inserted in an eyelet setting machine of the usual type.

3 is a shoulder designed to serve as a stop to limit the distance in which the thread 2 is screwed into the eyelet setting machine.

35 4 is the guiding end of the setting device which serves as a punch where the setting device combines a punch for punching a hole in which the eyelet is to be set when punching is combined with the setting operation.

40 5 is a setting or riveting shoulder which turns over and presses down the set or riveted portion of the eyelet.

There is a threaded portion 6 above the 45 setting shoulder 5 upon which is mounted the adjusting nut 7 so that said adjusting nut 7 may be turned up or down upon the threaded portion 6 to vary the distance between the side of the adjusting nut 7, contiguous to the setting shoulder 5 and said

50 setting shoulder. There is a spring-washer 8 inserted between the nut 7 and the side of the collar 3 next to it. This washer 8 is designed to produce a frictional contact be-

tween it and the upper side of the adjusting 55 nut 7 and lower surface of the shoulder 3 so as to retain the nut 7 in its adjusted position.

9 is a constricted or contracted portion between the setting shoulder 5 and the face of the adjusting nut 7 next to it. This constricted portion 9 is designed to permit the uppermost layer of material to pass above the setting shoulder 5 into the contracted portion 9 while the eyelet is being set in the lowermost layer or layers of material, as the 60 case may be.

This eyelet setting device is designed to set eyelets in one or more of the outside layers of a plurality of layers of flexible material. Where there are two layers of material cemented or fastened together in which it is desired to set the eyelet, the device is so constructed that it will set eyelets in said one or more layers, the setting shoulder passing through one of the outermost layers 70 to set the eyelet in the other one or more of the outermost layers, the contracted portion of the setting device being designed to allow the layer of material in which it is not desired to set the eyelet to be passed above the setting shoulder while the operation of setting the eyelet is being performed.

I do not confine my invention to the exact form of adjusting nut or spring-washer, or the body or contracted portion of the eyelet 85 setting device as shown in the drawings, as their shape or form may be varied without departing from the spirit of my invention.

What I claim is—

1. The combination of a punching and 90 eyelet setting device for setting eyelets in one or more of the layers of a plurality of layers of material, comprising a punch and a setting device having a projecting setting shoulder; a contracted portion above the setting shoulder; and an adjustable shoulder contiguous to said contracted portion.

2. A device for setting eyelets in one of a plurality of layers of a flexible material, 100 said device comprising a projecting setting shoulder; a contracted portion above the setting shoulder; and means constituting an adjustable shoulder contiguous to said contracted portion.

3. A device for setting eyelets in one of a plurality of layers of a flexible material, said device comprising a setting device having a projecting setting shoulder; a contracted 105

portion above the setting shoulder; an adjustable device contiguous to said contracted portion; and a frictional spring for maintaining said adjustable device in its adjusted 5 position.

4. A device for setting eyelets in one of a plurality of layers of a flexible material, comprising a setting device having a projecting setting shoulder; and adjustable 10 means above said setting shoulder for varying the distance between said setting shoul-

der and the underside of said adjustable means.

In testimony whereof, I have hereunto set my hand, in the presence of two subscribing 15 witnesses, this the 24th day of April, A. D. 1914.

FREDERICK S. GLINES.
